UNITED STATES PATENT OFFICE

ERNEST J. STEVENS, OF PHILADELPHIA, PENNSYLVANIA.

INHALER.

1,105,934.

Specification of Letters Patent.

Patented Aug. 4, 1914.

Application filed July 12, 1913. Serial No. 778,812.

To all whom it may concern:

Be it known that I, ERNEST J. STEVENS, a citizen of the United States, residing at Philadelphia, in the county of Philadelphia and State of Pennsylvania, have invented certain new and useful Improvements in Inhalers; and I do declare the following to be a full, clear, and exact description of the invention, such as will enable others skilled in the art to which it appertains, to make and use the same.

This invention relates to improvements in inhalers.

One object of the invention is to provide an inhaler having a plurality of detachable and interchangeable nose and mouth pieces by means of which the inhaler may be employed for a number of different purposes or in a number of different ways and where- 20 by the use of the inhaler is greatly facil- tated and its efficiency increased.

Another object is to provide an inhaler having means whereby the passage of the air therethrough may be regulated and 25 means whereby the medicament used therein may be supplied thereto without removing either the nose or mouth pieces thereof.

In the accompanying drawings: Figure 1 is a side view of my improved inhaler in its 30 simplest form, parts thereof being broken away and in section and the plugs for closing the ends thereof shown removed and in position for insertion; Fig. 2 is a vertical longitudinal section of a portion of the 35 outer end of the barrel or body of the inhaler illustrating the same arranged as a lung and voice developer; Fig. 3 is a view similar to Fig. 2 illustrating another arrangement of the inhaler for use as a lung 40 and voice developer; Fig. 4 is a side view of the inhaler showing the same provided with a double nose piece, parts being broken away and in section; Fig. 5 is a view similar to Fig. 4 illustrating the application of a sup- 45 plemental nose piece by means of which the inhaler may be hygienically used by two persons; Fig. 6 is a central longitudinal section of the inhaler arranged with the double nose piece as shown in Fig. 4 and as having 50 applied thereto a supplemental mouth piece whereby the inhaler may be hygienically used in the mouth by two people, this figure being taken on the dotted line 6—6 of Fig. 7; Fig. 7 is a vertical longitudinal sectional 55 view taken at right angles to and on the line 7—7 of Fig. 6; Fig. 8 is a detail cen-

tral longitudinal section of the supplemental nose piece; Fig. 9 is a diagrammatic view illustrating the use of the device as a nasal inhaler when arranged as shown in Fig. 1; Fig. 10 is a similar view illustrating the manner in which the device is used as a mouth inhaler when arranged as shown in Fig. 1; Fig. 11 is a similar view illustrating the use of the device when equipped with a double nose piece; Fig. 12 is a similar view illustrating the use of the device when equipped with the supplemental mouth piece; Fig. 13 is a similar view illustrating the use of the device when equipped with the supplemental nose piece; Fig. 14 is a similar view illustrating the use of the device when equipped with the voice and lung developing attachments shown in Figs. 2 and 3.

My improved inhaler comprises a barrel or tubular body 1 which may be of any suitable size and constructed of any suitable material. On one end of the barrel or body 1 is arranged a tapered or reduced nipple or mouth piece 2 which is preferably formed integral with this end of the barrel as shown and which has formed therethrough a central longitudinal passage 3. The nipple 2 has also preferably formed therethrough a transverse aperture 4 whereby the inhaler may be hung on a nail, hook or other support when not in use, and this aperture serves as a branch of the passage 3 when the suction is from the opposite end of the inhaler and said passage becomes the air inlet. In one side of the barrel or body 1, nearly midway between its ends but, if anything, a little nearer the end thereof having the nipple 2, is formed an auxiliary air inlet opening 5 which is provided with a plug 6 whereby the same may be opened or closed. When the plug 6 is removed from the opening 5 air will be drawn into the body of the inhaler through both the passage 3 in the mouth piece and the opening 5, whereas when the opening 5 is closed by the plug 6 all the air must enter through the passage 3 and its branches 4 if they are open. By this I mean to say that it is quite possible when the part 2 is held in the hand and the suction is upward throughout the device illustrated in the several views of the drawings, for the operator to put one or more fingers over the outer end of the passage 3 or either or both of its branches 4 and restrict the inlet of air, or it will be possible to close the

passage 3 with the plug 6 and admit air through the passage 5 and one or both of the branches, and in that case the inlet of air could be restricted by the tips of the fingers 5 in the same way. When this end 2 of the inhaler is used as a mouth piece it is possible to put the lips around it between the aperture 4 and the body and withdraw all the vapors from within the latter if the opening 10 5 is closed by the plug, it is possible to mix said vapors with some air by removing the plug, and it is possible to dilute the vapors yet more by slipping the lips outward along the mouthpiece until air is admitted through 15 both ends of the aperture 4. Thus it will be seen that this end of the device may be used as a mouth piece, or it may become the inlet end of the inhaler and the other end thereof may carry the mouth piece. With the opposite 20 end of the barrel or body 1 from that having the mouth piece or nipple 2 is adapted to be engaged a number of different styles of nose and mouth pieces or attachments whereby the inhaler may be employed for a 25 number of different purposes and in a number of different ways.

In Fig. 1 of the drawings wherein is shown the simplest form of the inhaler, the open end of the body or barrel 1 has engaged 30 therewith a single tapered nose piece 7. The nose piece 7 and the other attachments for the inhaler hereinafter described may be secured in the open end of the body or barrel 1 in any suitable manner, said open 35 end of the barrel, however, being here shown as preferably interiorly threaded to receive the exteriorly threaded inner ends of the attachments, said ends being preferably reduced to form annular stop shoulders a 40 whereby the inward movement of the threaded ends of the attachments is limited and a fluid-tight connection between the attachments and the barrel of the inhaler is obtained. When not in use the passage in 45 the nose piece 7 is adapted to be closed by a tapered plug 8, a similar plug 9 being provided to close the outer end of the passage 3 through the mouth piece 2, said plugs 8 and 9 being shown in Fig. 1 in position to 50 be inserted in their respective openings, which are also tapered to facilitate the tight engagement of the plugs and also to receive certain instruments used in physicians' offices, such for instance as the eustachian 55 catheter.

In Figs. 2 and 3 of the drawings the inhaler is shown as arranged for developing the lungs and voice and in this arrangement the nose piece 7 is removed and engaged with 60 the open end of the barrel 1 in place of said nose piece is a cap 10 having a reduced threaded extension 11 which is screwed into the end of the barrel and in which is formed a passage 12 which is preferably tapered for 65 a purpose hereinafter described. The device

when arranged in this manner is employed as an exhaler and when so used the medicament holder hereinafter described, is removed from the body of the device and the mouth piece is inserted in the mouth as 70 shown in Fig. 14 of the drawings. The air which has been drawn into the lungs by deep breaths through the nose or mouth is exhaled through the body of the device and through the opening 12 in the cap 10. The opening 75 12 is of such size that some effort is required to expel or exhale the air from the lungs and, if it is desired to increase the effort, the opening 12 is further restricted by the application of a reducing tube or nipple 13 of 80 suitable length and having therethrough a reduced air passage 14 through which the air must be forced when expelled from the lungs. The effort thus required in expelling the air through the restricted opening 12 or 85 passage 14 tends to exercise and develop the lungs and voice producing organs. The inner end of the tube or nipple 13 preferably tapers slightly and is adapted to be inserted into and to form an air tight engagement 90 with the tapered opening 12 in the cap 10 as clearly shown in Fig. 3 of the drawings.

In Fig. 4 of the drawings the device is shown as having applied thereto a double nose piece 15 whereby the inhaler may be applied to both nostrils at the same time and by means of which the use of the inhaler is expedited. The double nose piece 15 comprises a reduced exteriorly threaded barrel 95 engaging end 16 on which is formed the upwardly projecting branched nostril engaging tubes 17, the outer portions of which are preferably enlarged and are of substantially globular or oval shape to prevent the same from being inserted too far into the nostrils 100 and for effectually closing the latter so that nothing but the medicated air from the body of the inhaler can pass into the nostrils while the inhaler is being used. The passages through the branched nostril engaging tubes 105 110 of the inhaler are intersected where they join and at the center of the nose piece by an opening 18 the inner end of which connects with the body of the inhaler through an air discharging passage 19 formed in the neck 115 and communicating with the inner end of the nose piece as clearly shown in Figs. 6 and 7 of the drawings. The opening 18 is provided for a purpose hereinafter described and is normally closed by a plug 20 which is 120 engaged therewith as shown in Fig. 4 of the drawings but which does not close the passage through the tubes 17.

In Fig. 5 of the drawings the device is shown as equipped with the double nose 125 piece shown in Fig. 4 and in addition to the double nose piece has applied thereto a supplemental nose piece 21 having a globular or oval shaped outer portion 22 which terminates at its outer end in a reduced nostril 130.

engaging nipple 23 and which gradually tapers to a reduced neck 24 on the end of which is formed a tapered plug 25 which is adapted to be inserted into and to form a close engagement with the opening 18 in the neck of the double nose piece 15 as shown in dotted lines in Fig. 5 of the drawings. The supplemental nose piece 21 has formed therethrough a passage 26 through which the medicated air is drawn from the barrel of the inhaler. The plug shaped end 25 of the supplemental nose piece is of such length that when inserted in the opening 18 said plug 25 will close the inner ends of the passages through the tubes 17 of the nose piece and will connect the supplemental nose piece directly with the passage 19 in the neck of the double nose piece 15. The enlarged or globular shaped outer portion 23 of the supplemental nose piece serves to prevent the latter from being inserted too far into the nostrils and also serves to close the latter or to prevent the entrance of any outside air while the nose piece is engaged therewith.

In Figs. 6 and 7 the inhaler is also shown as having applied thereto the double nose piece 15 to which, in this instance, is connected a supplemental mouth piece 27 which takes the place of the supplemental nose piece 21 and adapts this end of the inhaler for use in the mouth. The supplemental mouth piece 27 is in the form of a substantially right angular shaped tube, the inner end of which is in the form of a tapered plug 28 adapted to be inserted into the tapered opening 18 in the neck of the double nose piece 15 as is clearly shown in Figs. 6 and 7 of the drawings. The outer end of the supplemental mouth piece or tube 27 is preferably slightly enlarged and rounded or of globular shape as shown. The plug shaped inner end 28 of the supplemental mouth piece also closes the inner ends of the passages through the tubes of the double nose piece and connects directly with the air passage in the neck of the latter. By providing the supplemental nose piece 21 and mouth piece 27 it will be seen that the inhaler may be hygienically used by two people or without danger of conveying the disease of one person using the same to another which would be apt to occur if the same nose and mouth pieces were used by both parties. The barrel or body of the inhaler is adapted to contain a perforated tubular holder or cage 30 which is of slightly less length and diameter than the inner length and diameter of the barrel, and in this holder is placed a suitable absorbent material 31 which is adapted to be saturated with and to hold the medicament in position for coming into contact and mixing with the air drawn through the barrel or body of the inhaler. The medicament may be placed on the absorbent material 31 by removing the nose piece or other closures from the open end of

the barrel or, if desired, the medicament may be applied to the absorbent material 31 in the holder or cage 30 through the opening 5 in one side of the barrel preferably by means of a glass dropper, this being the preferred method of renewing the medicament. In any case, however, it is clear that the medicament will eventually settle to whichever is the lower end of the absorbent while the device is in the position in which it is used, and it does not need illustration to show that this end of the absorbent will remain moist and the other end will give off its vapors into the air drawn through the inhaler, and eventually become quite dry or at least drier than the saturated end which we will call the lowermost end. When now the inhaler is to be used again or by another person, if the full strength of the medicament is desired the opening 5 is plugged and the mouth piece or opening at one end is drawn upon while the inlet at the other end is left wide open. If not so much air is desired, the inlet may be restricted in the manner above suggested. But if the fumes or vapors are too strong the plug 6 may be withdrawn and air will be admitted through the passage 5 above the most thoroughly saturated portion of the absorbent, whichever end of the latter it may be that is so saturated, and this air mixing with that admitted through the inlet, or even used when the inlet is closed, will eventually find its way to the patient. If he or she is using the inhaler in one position constantly, it is quite possible to remove the holder 30 and invert it if the conditions just described are objectionable or if they could be improved at any time by such inversion. Therefore I consider it one of the features of my invention to provide an inlet opening or passage 5 through the side wall of the barrel between its ends, and to regulate or perhaps to close this opening by means of the plug or the tip of the finger, and in connection with such an opening to employ a cartridge or holder containing absorbent and which is invertible or reversible within the barrel.

From the foregoing description taken in connection with the accompanying drawings, the construction and operation of the invention will be readily understood without requiring a more extended explanation.

Various changes in the form, proportion and the minor details of construction may be resorted to without departing from the principle or sacrificing any of the advantages of the claimed invention.

Having thus particularly described my invention what I claim is:

The herein described inhaler comprising a tubular barrel having an opening in one side substantially midway between its ends, a longitudinally projecting tubular nipple at one extremity communicating with the inter-

rior of the barrel and having its inlet end of the same size as said opening, the nipple being pierced with a transverse aperture intersecting its bore, a plug removably fitting said opening in the barrel and inlet end of the nipple, a perforated cap removably closing the other end of the barrel, a cylindrical perforated holder removably and invertibly disposed within said barrel, and an ab-

sorbent within the holder adapted to contain 10 a medicament.

In testimony whereof I have hereunto set my hand in presence of two subscribing witnesses.

ERNEST J. STEVENS.
